UNITED STATES PATENT OFFICE.

CARL WINKLER, OF BERNE, SWITZERLAND.

IMPRESSION-CYLINDER FOR PRINTING-MACHINES.

1,314,452.

Specification of Letters Patent. Patented Aug. 26, 1919.

Application filed June 26, 1918. Serial No. 242,063.

To all whom it may concern:

Be it known that I, CARL WINKLER, a citizen of the Swiss Republic, residing at Berne, in the Swiss Republic, have invented a new 5 and useful Improved Impression-Cylinder for Printing-Machines, of which the following is a specification.

In the design of modern printing machines, particularly of machines having a 10 reciprocating type-carriage, continual efforts are being made so to strengthen and stiffen the parts which are normally and especially subject to strains and distortion during the time printing is in progress, that 15 good and exact prints are obtained for the duration of the entire "life" of the machine. Hitherto attention has chiefly been paid to the proper construction of the side frames, cross frames and under-frames. With that 20 end in view certain parts have been reinforced or strengthened so that the strains are better distributed and improved printing results are obtained. The impression cylinder was, however, liable to be badly affected by such measures, because the strains 25 were more concentrated on the same, and after some time it became impossible to obtain good prints.

The object of the present invention is to 30 overcome or avoid these drawbacks, the main purpose of the invention being so to strengthen the impression cylinder, in addition to the side and transverse frames, that the resistance to bending or distortion 35 reaches a maximum. For this purpose the impression cylinder is so constructed, according to the present invention, that the longitudinal ribs or webs inside the same have a width which corresponds with the in- 40 side diameter, and a length corresponding with the entire length, of the cylinder. Owing to the fact that the cylinder-rim, the transverse and longitudinal ribs, and the trunnions can all be cast in one piece, the

cylinder is rendered considerably stronger 45 and more durable.

In the annexed drawing one form of carrying out the invention is illustrated by way of example.

Figure 1 is a longitudinal section of the 50 impression cylinder on the line 1—1 of Fig. 2.

Fig. 2 is a cross section on the line 2—2 of Fig. 1.

Fig. 3 shows the cylinder in elevation and 55 Fig. 4 is an end view of the same.

As will be seen from the drawings, the longitudinal ribs *a* are radially arranged and meet together at the axis of the cylinder; they thus connect the outside walls 60 *b c d* of the impression cylinder both in a radial and a longitudinal direction. Further, it is evident that these ribs can be made without apertures or openings and that the longitudinal and transverse ribs *a'*, 65 cylinder end walls, cylinder rim and trunnions are capable of being made in one piece.

What I claim and desire to secure by Letters Patent of the United States is:—

1. An impression cylinder for printing 70 machines comprising an axis, end walls and radially disposed internal longitudinal ribs, merging integrally with said axis, said ribs integral with the cylinder and end walls and extending uninterruptedly from end wall to 75 end wall.

2. An impression cylinder for printing machines including a shell, end walls, axis and trunnions cast integral and longitudinal internal imperforate ribs radially disposed 80 and merging with said axis and end walls.

In testimony whereof I have signed my name to this specification in the presence of two subscribing witnesses.

CARL WINKLER.
